UNITED STATES PATENT OFFICE

100,215

DESIGN FOR A SAFETY TREAD PLATE

John M. Klipfel, Elizabeth, N. J., assignor to
Socony-Vacuum Oil Company, Incorporated,
New York, N. Y., a corporation of New York

Application April 15, 1936, Serial No. 62,141

Term of patent 14 years

To all whom it may concern:

Your petitioner, John M. Klipfel, a citizen of the United States, residing at Elizabeth, in the county of Union, State of New Jersey, have invented a new, original, and ornamental Design for a Safety Tread Plate, of which the following is a specification, reference being had to the accompanying drawing, forming a part thereof, wherein:

Figure 1 is a plan view of a safety tread plate made in accordance with this design;

Figure 2 is an edge view of the safety tread plate shown in Figure 1; and

Figure 3 is a perspective view of a portion of a safety tread plate made in accordance with this design.

I claim:

The ornamental design for a safety tread plate as shown.

JOHN M. KLIPFEL.
